RINGING CONTROL SYSTEM FOR TELEPHONE-EXCHANGES.

1,251,604.

Specification of Letters Patent.

Patented Jan. 1, 1918.

Application filed December 28, 1915. Serial No. 69,066.

To all whom it may concern:

Be it known that I, SAMUEL B. WILLIAMS, Jr., a citizen of the United States, residing at Brooklyn, in the county of Kings and 5 State of New York, have invented certain new and useful Improvements in Ringing Control Systems for Telephone-Exchanges, of which the following is a full, clear, concise, and exact description.

10 This invention relates to a ringing control system for telephone exchanges, and is particularly designed for use in connection with party telephone lines in which the several stations are selectively signaled by the 15 application of distinctive signaling or ringing currents at the central office.

The principal object of this invention is to provide means, which may be in part common to all of the connecting circuits of 20 a position and in part individual to the various circuits, for enabling the operator to predetermine and control the character of ringing current that is automatically applied in establishing connection with a line, 25 to ring a particular station of that line, and to ascertain the sort of ringing current a particular connecting circuit is set to apply.

The system of this invention is such that 30 the setting of the operator's switching apparatus to predetermine the character of ringing current that is to be applied automatically by a particular connecting circuit, brings about certain changes in said circuit 35 which not only are instrumental in controlling the character of the signaling current that this circuit is thus adapted to apply, but also control the display of a corresponding one of a number of signals associated 40 with the operator's switching apparatus to indicate to the operator, when she listens in on this connecting circuit, the sort of ringing current for which the connecting circuit is set. The organization of the system is 45 such that when a connecting circuit is changed through the agency of the operator's switching mechanism to adapt it for the application of a certain sort of ringing current, it remains set to apply this sort of 50 current until the connection is taken down or until the operator manipulates her switching mechanism to change the setting while listening in on the connecting circuit.

The selective application of ringing current to the connecting circuit is preferably 55

effected through the agency of an automatic switch of the "sequence switch" type, this switch being arranged to establish the different ringing current combinations in different positions of its movement, and being 60 arranged to move to any predetermined one of its ringing positions under the control of the individual connecting circuit controlling mechanism set by the switching apparatus common to the position.

65 The above mentioned and other features of the invention will be described in detail in connection with the accompanying drawing, which illustrates one of the forms in which the invention may be practised.

In the particular embodiment illustrated, the invention is shown applied to a connecting circuit terminating in a plug 11, the plug being adapted to be inserted in a spring jack 12 upon which the telephone 75 line terminates. The telephone line 13, 14 is illustrated as extending to four substations, M', J', R' and W', each of which is provided with the usual substation equipment, which may comprise a telephone 80 transmitter and receiver, an induction coil, a condenser and a switch hook for controlling the circuit. In addition, there is at each substation a bell which is bridged, through the condenser, from one side or the 85 other of the telephone line to ground. The bells at substations M' and J' are bridged to ground from the conductor 13, and those at stations R' and W' from conductor 14 of the telephone line.

90 Only the calling end of the connecting circuit E is illustrated. The other end of the connecting circuit may be assumed to extend to apparatus suitable for making connection with a calling line and for controlling such connection, the circuit between the answering and calling ends of the connecting circuit having included in it a repeating coil 10 with a bridged battery 15, in the usual way.

95 The talking conductors 16 and 17 of the connecting circuit terminate upon the tip and ring contact surfaces, respectively, of the calling plug 11. The sleeve contact surface of the plug is the terminal of a conductor 18, which extends from the free pole of the battery 15 and includes the windings of two relays 19 and 20. When the plug 11 is inserted in a spring jack 12, the 100 circuit of this conductor 18 is completed to 110

ground by way of the winding of the cut-off relay 21, thus bringing about the energization of the relays 19, 20 and 21. The relay 21 has the usual function of disconnecting 5 from the line, during its use, the branches that lead to the usual line signal apparatus (not shown). Relay 19 in operating, disconnects the tip of the plug from the operator's busy test circuit (not shown) and connects it with the talking conductor 16. The relay 20 in operating, closes a circuit for the flow of current through the calling supervisory lamp 22, subject to the control of contacts 114 closed in position 17 of a calling 10 cord sequence switch that will be referred to hereinafter. After the circuit of the calling lamp 22 is closed by the actuation of the relay 20, when the calling plug is inserted in the spring jack, the illumination 15 of the lamp is under the control of the called subscriber in the usual way through the medium of the calling supervisory relay 24, the shunt of the lamp controlled by this relay being also under the control of contacts 112 20 closed in position 17 of the calling cord sequence switch.

The calling cord sequence switch 100 may be similar to that illustrated in Patent #1,127,808 to J. N. Reynolds and C. F. 30 Baldwin, dated February 9, 1915, or of any other suitable type. The sequence switch 100 controls sequence switch contacts 101 to 114, inclusive. Contact 101 of the sequence switch is arranged to close the local circuit 35 for the sequence switch operating magnet in all positions of the switch except those indicated by the figures adjacent to contact 101. This provides that the switch may stop only in the positions indicated. The other 40 sequence switch contacts 102 to 114 inclusive, are closed only in the positions indicated by the figures adjacent to the respective contacts.

The positions of the calling cord sequence 45 switches are as follows:

Pos.	1	Normal
	"	2 Awaiting listening key sequence switch
	"	4 Awaiting pick-up
50	"	5 Ringing station M' on tip
	"	7 Awaiting pick-up
	"	8 Ringing station J' on tip
	"	10 Awaiting pick-up
	"	11 Ringing station R' on ring
55	"	13 Ringing station W' on ring
	"	16 Awaiting supervisory relay
	"	17 Talking

Ringing current is supplied to the connecting circuit by way of a conductor 25, 60 which has branches 26 and 27 at one end that are adapted under certain conditions to be completed to the tip and ring conductors, respectively, of the calling plug 11, and branches 28 and 29 at the other end which 65 are adapted under certain conditions to be

completed to sources of two different sorts of ringing current. In the present instance, the ringing generator 30 has associated with it three commutators 31, 32 and 33. The commutator 31 is adapted, during each cycle 70 of its rotation, to connect the conductor 29 for an interval with generator 30, and during the balance of the cycle connect it with the free pole of battery 15. Commutator 32 is adapted, during each cycle of its rotation, 75 to connect the conductor 28 twice with the ringing generator 30 and twice with the free pole of the battery 15 alternately. The arrangement is such that when the branch, by way of the conductor 29, is connected with 80 the cord circuit, a single long impulse of ringing current is applied to one or the other side of the line, depending upon which of the branches 26 and 27 is closed at the time; while when the branch 28 is connected with the cord circuit, two short ringing impulses are applied to one side or the other of the line, with a relatively long interval of silence between each group of two short rings. The pick-up commutator 33 rotates 85 with the commutators 31 and 32, and is arranged to send one impulse of current per rotation from the battery 15 out over the circuit in a manner hereinafter to be described, for the purpose of marking the 90 cycles of rotation of the commutators.

The organization described above provides ringing current for a plurality of the connecting circuits, and is one of those that may be employed for producing different sorts 100 of ringing current for the selective or distinctive ringing of bells at the various substations of a party line. A number of other methods of selectively or distinctively ringing party line bells are available in the art 105 and may be employed, such as those which depend upon the use of polarized pulsating currents in connection with polarized and biased bells, and those depending upon different frequency currents and so-called harmonic or tuned bells, and it will be understood that ringing generators and bells of these other sorts may be substituted for those particularly disclosed herein, without departing from the spirit and scope of this invention. 115

The branch 26 of the conductor 25 has its connection with the tip side of the connecting circuit controlled in sequence switch contacts 104-5 and 104-8, while branch 27 120 has its connection with the ring side of the connecting circuit controlled in sequence switch contacts 105-11 and 105-13. The connection between the other end of the conductor 25 and the two branches 28 and 29, over which the two sorts of ringing currents are supplied from commutators 32 and 31, is controlled by sequence switch contacts 106, branch 28 being connected with conductor 25 in positions 106-5 and 106-11, while 125 130

branch 29 is connected in positions 106—8 and 106—13 of the switch contacts. That is, in position 5 of the sequence switch 100, source 30, 32 of ringing current is connected 5 with the tip strand of the connecting circuit; in position 8 of the sequence switch, source 30, 31 is connected with the tip strand, in position 11, source 30, 32 is connected with the ring strand, and in position 13, 10 source 30, 31 is connected with the ring strand of the connecting circuit. Contacts 105—5, 105—8, 104—11 and 104—13 of the sequence switch operate to establish a ground connection from one side of the connecting circuit when the other side of the circuit is connected to one or the other of the sources of ringing current.

In the particular embodiment of the invention illustrated, the control of the ringing current so as to ring any one of the four stations of a party line is effected through the medium of four selective keys M, J, R, and W, which are common to all of the connecting circuits of the operator's position.

25 Other connecting circuits organized similarly to the one shown, are indicated by the taps which are represented as extending from the conductors that lead to the common selective keys and their associated lamps m, 30 j, r, and w. The selective keys M, J, R, and W act through the medium of relays 38, 39 and 40, individual to each connecting circuit, to determine which one of four branches 41, 42, 43, and 44 of a controlling circuit 45 shall have its circuit closed. These branches 35 41, 42, 43 and 44 are brought successively into operative relation with the controlling conductor 45 in the movement of the sequence switch 100 and through the medium 40 of their respective associated sequence switch contacts 107—3 to 5, 108—6 to 8, 109—9 to 11, and 110—12 to 13. The completion of 45 the controlling conductor 45 through one or another of the branches 41, 42, 43 and 44 in the movement of the sequence switch acts 50 through the medium of relay 36 included in the controlling circuit to complete the circuit of the ringing conductor 25 in the contacts 34 of that relay, and to control the stopping of the sequence switch in position to 55 close the branches of the ringing circuit for ringing the particular party line station that corresponds with the particular selective key M, J, R, or W that has been depressed and the particular branch 41, 42, 43 or 44 of the controlling circuit that has been closed.

Assuming that the operator has received a call for station W' of the particular line that is illustrated in the drawing, and that 60 the call has come over the connecting circuit that is shown in the drawing. Under such circumstances the operator has her telephone set and controlling apparatus in connection with the particular cord circuit illustrated, and the switch contacts 202, 203, 204,

205, 207 and 208, which may be contacts associated with a listening key sequence switch, of which there would be one for each connecting circuit, are closed. The closure of these contacts, only one set of which may 70 be closed at a time, connects the selecting keys M, J, R, and W common to the operator's position with the particular connecting circuit that is to be used in establishing the connection. This places the ringing control 75 devices of this particular connecting circuit under the control of the common selecting keys M, J, R and W.

The arrangement of the ringing current controlling devices of each connecting circuit is such that normally the branch 44 of the controlling circuit 45 has its connection with earth completed by way of the back contacts 46, 47 and 48 of the relay 38, 39 and 40, respectively; and therefore, if the 80 apparatus is in its normal condition, it is not necessary for the operator to depress the selecting key W. She inserts the calling plug 11 into the spring jack 12. This act, 85 through the agency of circuits and apparatus that need not be particularly described, completes the local circuit of the calling cord sequence switch operating magnet by way of sequence switch contact 102—1, and moves the sequence switch out of position 90 1 and into position 2. When the operator's telephone set and controlling apparatus is disconnected from the connecting circuit,— 95 which may result either from the operator's listening out manually, or from a sequence 10 switch that is assumed to control the switch contacts 202 to 208, inclusive, being moved as a result of the closure of the circuit due to inserting the plug 11 in the spring jack 12,—the local circuit of the calling cord 10 sequence switch 100 is closed by way of sequence switch contacts 103—2 to move the sequence switch out of position 2.

As sequence switch 100 moves into position 3, it closes in sequence switch contacts 111, a path to ground for whichever of the branches 41, 42, 43 and 44 may be closed in the relay contacts 46, 47 and 48. In the particular case being described, as the relays 38, 39 and 40 are inert, it is the branch 44 115 that thus is given a ground connection.

As the sequence switch 100 moves into position 4, its further movement comes under the control of the normal or resting contacts 35 of relay 36 by way of sequence switch contacts 103—4 to 13. Therefore, beyond position 4 the movement of the sequence switch 100 will continue only as long as relay 36 remains inert. As sequence switch 100 moves from position 3 to position 11 inclusive, it brings the controlling conductor 45 120 successively into communication with the branches 41, 42 and 43 by the successive closure of the sequence switch contacts 107, 108 and 109. But as each of these branches 125 130

is open in its associated relay contacts, nothing happens.

When sequence switch 100 comes to position 12, it closes sequence switch contacts 110, and thus completes a path to ground for controlling conductor 45 by way of branch 44, the resting contacts 48, 47 and 46 of relays 40, 39 and 38 respectively, and sequence switch contacts 111. This affords 5 a path for current flow through relay 36, and the consequent energization of that relay opens its back contacts 35 and interrupts in these contacts the local energizing circuit of the sequence switch 100 by way of contacts 103, thus causing the sequence 10 switch to come to rest in position 13 upon the opening of the alternative energizing path that it has in position 12 by way of sequence switch contact 101. In position 13 15 contacts 103, thus causing the sequence switch to come to rest in position 13 upon the opening of the alternative energizing path that it has in position 12 by way of sequence switch contact 101. In position 13 20 of the sequence switch 100, ringing current from the source 30, 31 is supplied to the line to ring the bell at station W', the path of flow being from ringing generator 30 through commutator 31, branch 29, sequence switch contacts 106-13, winding of 25 relay 49, contacts 34 of relay 36, conductor 25, branch 27, sequence switch contacts 105-13, registering ring contact surfaces of plug 11 and spring jack 12, line conductor 14, through the condensers and bells at stations R' and W' to ground. The subscriber at station R' does not respond, because his signal is two short rings instead 30 of the one long ring per cycle that is being given. 35

When the subscriber at station W' takes his receiver from the hook, the relay 49 included in the ringing circuit is energized and opens its contact 50. The relay 49 is 40 so constructed and adjusted as to be unresponsive to the current that flows through it during the ringing of the called station, but to respond when the called subscriber takes his telephone from the hook. The 45 opening of the contact 50 of the relay 49, on the response of the called subscriber, opens the short-circuit that has hitherto existed around the winding of relay 51, thus permitting the current flowing in the controlling conductor 45 to pass through and energize relay 51. When this relay operates, it introduces, in its contacts 52, another break in the above mentioned short-circuit to insure the continued energization of relay 50 55 51 after relay 49 becomes inert, and also in its contacts 53 closes a path to battery through a relatively low resistance coil 54 in shunt of the winding of the relay 36 to bring about the deenergization of the last 60 mentioned relay.

When relay 36 becomes inert, it permits the closure of its back contact 35, thus again closing the local energizing circuit of the sequence switch 100 by way of sequence 65 switch contacts 103-13. Therefore the

sequence switch moves out of position 13 and continues its movement to position 16, where it is stopped by the opening of its energizing circuit in contacts of its 101 cam. In position 16 of the sequence switch, the sequence switch contacts 104 and 105 are closed to connect the tip and ring of the plug 11 with the conductors 16 and 17 respectively of the connecting circuit, the plug having been disconnected from its ringing current 70 connections when the sequence switch moved out of position 13. As the called subscriber has his telephone off its hook, supervisory relay 24 is energized and closes the local circuit of sequence switch 100 by way of sequence switch contacts 102-16. This causes 75 the sequence switch to move to position 17, which is the talking position.

While the conversation is proceeding and the called subscriber has his receiver off its 80 hook, supervisory relay 24 keeps the shunt of the calling supervisory lamp 22 closed by way of sequence switch contacts 112-17. When the called subscriber replaces his receiver, relay 24 becomes inert and permits 85 lamp 22 to light. The operator in taking down the connection brings about the closure of the local energizing circuit of sequence switch 100 by way of contacts 102-17, and the sequence switch in consequence moves to position 1, thus restoring 90 the circuits to their normal condition.

The operation described above was under the assumption that it was station W' that was to be signaled. If it is station R' that 100 is to be called, the operator presses key R of her common selecting keys M, R, J, and W, while listening in on this particular connecting circuit. In this condition the switch contacts 202, 203, 204, 205, 207 and 208 are 105 closed and the circuits of the common selecting keys are connected with this cord circuit. Pressing the selecting key R energizes relay 40 over the path by way of contacts 204, contacts 59 of key R and resting contacts 58 and 56 of keys J and M, respectively, to ground. Upon the release of selecting key R, after a momentary depression, a holding circuit is closed for relay 40 by way of front contacts 63 of that relay, resting 110 contacts 64 and 65 of relays 39 and 38 respectively, contacts 207 closed while the operator is in on this circuit, and resting contacts 62, 60, 58 and 56 of the selecting keys to ground. Relay 40, thus held energized, 115 completes the circuit of branch 43 to ground by way of the front contact 48 of relay 40 and the resting contacts 47, 46 of relays 39 and 38 respectively, and sequence switch contacts 111 in positions 3 to 13 of the sequence 120 switch.

The consequence of this is that when sequence switch 100, in moving beyond position 4, reaches position 9 and closes switch contacts 109 associated with the grounded 125 switch.

branch 43, an energizing circuit for relay 36 is completed, which causes that relay to open its resting contact 35, thus breaking the local energizing circuit of the sequence 5 switch closed in switch contacts 103, and bringing the switch to rest in position 10. As the ringing code employed in this system depends upon one or more rings having a certain relation to each other, it is desirable 10 that the application of ringing current to the circuit occur only at a particular point in the ringing cycle. To accomplish this the arrangement is such that the sequence switch is brought to rest at a position one point 15 before that at which the particular ringing current selected is to be applied, and is moved from this waiting to the ringing position by a pick-up impulse produced at the beginning of each ringing cycle by the commutator 33. This action is effected through 20 the medium of the relay 37. When the relay 36 is energized, the circuit of the relay 37 is completed to ground by way of the front contacts 35 of relay 36. The connection of relay 37 with the battery is completed 25 once for each ringing cycle by means of the pick-up commutator 33. Therefore, at the start of the first ringing cycle after relay 36 has closed its contacts 35, the relay 37 30 receives current for its energization by way of the pick-up commutator 33; and in operating its contacts 66, relay 37 disconnects its winding from the pick-up commutator and connects it directly to battery, so that there 35 after the relay 37 remains energized as long as its circuit is completed in the contacts 35 of relay 36. When the first pick-up impulse, after relay 36 was operated, energizes relay 37, that relay closes in its contact 67 an energizing circuit for sequence switch 100 by 40 way of sequence switch contacts 103 in positions 4, 7 or 10, these three positions being those in which the sequence switch waits upon the receipt of a pick-up impulse before 45 it moves to the immediately succeeding position where the selected ringing current is applied.

The present assumption is that by reason of the depression of the key R having 50 brought about the closure of the branch 43, the sequence switch 100 has been stopped in position 10, where it is awaiting the next pick-up impulse. Upon receipt of the pick-up impulse, the relay 37 closes its contact 55 67, and the sequence switch is moved from position 10 to position 11. In position 11, sequence switch contacts 106 are closed to direct ringing current from source 30, 32 to ringing conductor 25, and sequence switch 60 contacts 105 are closed to connect the ringing current thus applied to conductor 25 with the ring side of the connecting circuit, and thence by way of conductor 14 of the line circuit to stations R' and W'. The bells at 65 both stations ring, and the subscriber at sta-

tion R', whose ringing code signal is being given, answers. The taking of the receiver from its hook at station R' brings about the energization of relays 49 and 51 and the de-energization of relay 36 in the same manner 70 as was described in connection with the ringing of station W'. When relay 36 is de-energized, it closes in its resting contacts 35 the local energizing circuit of the sequence switch 100 by way of sequence switch contacts 103-4 to 13, thus causing the sequence switch to move continuously from position 11, through position 13, whence the movement is continued by way of sequence switch contacts 101 to position 16, out of which position it is moved in the manner described 75 in connection with the ringing of station W'. If it is assumed to be station J' that is to be signaled, the operator, while having her common selecting keys M, J, R and W as- 80 sociated with this particular connecting circuit, depresses selecting key J. This causes the energization of the relay 39 by way of switch contacts 203, contacts 57 of selecting key J, and resting contacts 56 of selecting key M to ground; and upon the release of the common selecting key J, after a momentary depression, the energization of relay 39 is maintained by way of a circuit that in- 85 cludes the front contact 64 of relay 39, rest- 90 ing contact 65 of relay 38, contacts 207 closed while the operator is in on this circuit, and the resting contacts 62, 60, 58 and 56 of the four selecting keys, to ground. As a 95 result, branch 42 of the controlling circuit 100 is completed to ground by way of the front contact 47 of relays 39, resting contact 46 of relay 38 and contacts 111-3 to 13 of the sequence switch, while the other branches 105 41, 43 and 44 remain open. Consequently, when sequence switch 100 reaches position 6 and closes sequence switch contacts 108 with which branch 42 is associated, relay 36 110 opens its contact 35 to stop the sequence switch in the next open position 7 of the controlling contacts 101, and its contacts 34 to close the ringing conductor 25 in readiness for the application of ringing current to the circuit. Relay 36, in closing its front contact 35, also places relay 37 in readiness 115 to be operated upon the occurrence of the next pick-up impulse, this operation of relay 37 acting, by the closure of its contact 67, to close the local energizing circuit of the sequence switch 100 by way of sequence 120 switch contacts 103-7, thus moving the sequence switch into position 8.

In position 8 of the sequence switch, contacts 106 of the switch connect ringing current from commutator 31 with ringing conductor 25, and contacts 104 of the switch connect conductor 25 with the tip side of the circuit and thence, by way of line conductor 13, ringing current flows through the bells 125 at stations M' and J'. As the current that 130

is being applied is such as to give the code signal to which station J' responds, the subscriber at that station takes his receiver from its hook. Thereafter the operation is as has 5 been described in connection with the ringing of stations W' and R' , the taking of the receiver bringing about the deenergization of relay 36 to disconnect the ringing current and move the sequence switch from the position 8, in which it has been resting, through position 13, and thence to the talking position 17.

When it is station M' that is to be signaled, the operator momentarily depresses 15 the common selecting key M while listening in on the connecting circuit that is to be used. This causes the initial energization of relay 38 by way of switch contacts 202 and contacts 55 of the selecting key M , and 20 the continued energization of relay 38, after the key M is released, by way of switch contacts 207 and contacts 62, 60, 58 and 56 of the four selecting keys in series. This closes branch 41 to ground in the front contacts 46 25 of relay 38, the other three branches 42, 43 and 44 being left open. In this case, therefore, relay 36 is energized as soon as the sequence switch 100 reaches position 3, in which it closes its contact 107 associated with branch 41, and the sequence switch comes to 30 rest in the next open position 4. Here it awaits the next pick-up impulse, which operates through relay 37 to close the local energizing circuit of the sequence switch by way 35 of contacts 103—4 and move the sequence switch into position 5. In position 5, sequence switch contacts 106 connect ringing current from the commutator 32 with conductor 25, and sequence switch contacts 40 104 connect the ringing current thus applied to conductor 25 with the tip side of the connecting circuit, and thence by way of line conductor 13 to the bells at stations M' and J' . Under these 45 conditions the bells ring the code signal of station M' , and the subscriber at that station responds. The taking of the receiver from its hook at the called station acts, in the manner already described, to deenergize relay 36, thus disconnecting ringing current from the line and closing the local energizing circuit of sequence switch 100 to move that switch out of position 5, in which it has been resting, through position 50 13, and eventually into the talking position 17, as has already been described.

In each case relay 51, locked up as a result of the response of the called subscriber, is released, upon the resumed movement of the 55 sequence switch, by the breaking of its circuit in whichever of the sequence switch contacts 107, 108, 109 or 110 had its branch closed to effect the signaling of the corresponding station.

60 65 When the operators' common selecting

keys M , J , R and W have been brought into association with any one of the connecting circuits, and have been manipulated to set the apparatus associated with that circuit for the application of a particular sort of 70 ringing current to the line, that setting of the connecting circuit apparatus is maintained until the connection is taken down or until the operator brings about a different setting of the cord circuit apparatus by 75 pressing some other selecting key while listening in on this circuit. This, in the particular embodiment of the invention illustrated, is accomplished by the manner in which the holding or maintaining circuits 80 for the setting relays 38, 39 and 40 of the connecting circuit are made subject to the control of switch contacts associated with the selecting keys, the operator's controlling circuits and the connecting cord circuit itself. 85 The common holding or maintaining circuit for the relays 38, 39 and 40 has two branch paths to ground, one of these branches being closed in the switch contacts 207, while the operator is listening in on the connecting circuit, and the other being closed in contacts 206 while the operator has her telephone and controlling apparatus disconnected from the connecting circuit. The contacts 206 and 207 are so arranged that 90 one of them is always closed before the other is opened, so that one or the other of the branches of the holding circuit is closed at this point at all times. The branch by way 95 of the contacts 206 extends to earth by way of contacts 113 closed in positions 1 $\frac{1}{2}$ to 17 $\frac{1}{4}$ of the sequence switch 100, while the branch completed in the contacts 207 extends to ground by way of the normal or resting contacts 62, 60, 58 and 56 in series of the selecting keys W , R , J and M .

As a result, after any one of the relays 38, 39 and 40 has been operated by the depression of the corresponding selecting key, it is held operated by one or the other of the branches of the holding circuit as the operator listens in or listens out on the circuit. When the connection is taken down, it being assumed that the operator is not in on the circuit at the time and that the contacts 206 are therefore closed, the relay 38, 39 or 40 that has been operated is released by the opening of the holding circuit in the sequence switch contacts 113 as the sequence switch 100 returns to its normal position 1. 100 The sequence switch 100 is moved out of position 17 and into position 18 upon the deenergization of relay 19 resulting from the removal of plug 11 from the jack 12. The driving circuit may be traced from ground, 105 through the armature and back contact of relay 19, the sequence switch contact 102, positions 2 to 17, and the power magnet of sequence switch 100 to grounded battery. 110 If the operator desired to change the set- 115 120 125 130

ting of the connecting circuit in order to bring about the application of a different sort of ringing current to the called line, she listens in on the circuit, and then may 5 withdraw the calling plug 11, press the particular one of the selecting keys M, J, R and W corresponding with the desired setting, and reinsert the plug; whereupon the sequence switch 100, which was returned to 10 its normal position by the withdrawal of the plug, is moved to the position determined by the new setting of the selecting keys.

In the operator's listening-in position, the closure of switch contacts 207 places the 15 holding circuit for the relays 38, 39 and 40 under the control of the series of normally closed contacts 62, 60, 58 and 56 of the four selecting keys. Consequently, the depression of any one of these keys releases which- 20 ever of the relays 38, 39 and 40 is locked up by opening the corresponding set of holding contacts 62, 60, 58 or 56. The accompanying closure of the contacts 55, 57 or 59 closes the circuit for the energization of the corre- 25 sponding relay 38, 39 or 40, depending upon the new setting desired, and the release of the selecting key M, J or R closes the common holding circuit for the operated relay by way of the contacts 56, 58 or 60 before it 30 opens the individual operating circuit of the relay by way of the contacts 55, 57 or 59. As the setting corresponding with the selecting key W is the normal setting of the connecting circuit, that key when depressed 35 operates merely to restore the normal setting by releasing any one of the relays 38, 39 and 40 that may be held up through the common holding circuit.

In order that the operator may know the 40 ringing current for which a connecting circuit is set, each of the selecting keys M, J, R and W has associated with it a lamp, *m*, *j*, *r* and *w*, respectively, and the circuit arrangement is such that when the operator 45 listens in on a connecting circuit, the lamps, corresponding with the sort of ringing current for which the circuit is set, lights. This is accomplished by connecting the lamps *m*, *j*, *r*, and *w* with the circuits which 50 extend from their corresponding keys to the switch contacts 202, 203, 204, and 205, and providing the lamps with a common connection to battery by way of switch contacts 208 closed when the operator listens 55 in on the circuit. If any one of the three 60 relays 38, 39 and 40 is up at the time the contacts 202, 203, 204 and 205 are closed by the operator going in on the connection, a path to ground for the circuit including 65 the corresponding lamp *m*, *j*, or *r* is closed by way of the front contact 63, 64 or 65 of the operated relay and the branch of the holding circuit that extends through the contacts 207 and the resting contacts 62, 60, 58 and 56 of the selecting keys in series. If

none of the relays are up when the operator listens in, and the setting consequently is the normal setting for the ringing of station W', the path for the flow of current to lamp *w* is completed by way of the resting contacts 63, 64 and 65 of the three relays, contacts 207, and the resting contacts of the four selecting keys in series. 70

What is claimed is:

1. The combination with a telephone connecting circuit, of a ringing circuit having a plurality of branches a controlling circuit having a corresponding number of branches with a key in each branch for closing the same, and an automatic switch adapted in 80 its movement successively to establish the branches of said ringing circuit and simultaneously bring itself under the control of the corresponding branch of said controlling circuit. 85

2. In a telephone system, the combination with a plurality of connecting circuits, of a plurality of electromagnetic ringing control switches for each connecting circuit, operator's means common to said connecting circuits for selectively operating the electromagnetic ringing control switches of any one of the connecting circuits, and signals associated with said operator's means, said signals being selectively controlled by the 90 electromagnetic switches of an associated connecting circuit. 95

3. In a telephone system, the combination with a plurality of connecting circuits each having a plurality of ringing control 100 switches associated therewith, of operators' indicating means common to said connecting circuits, said indicating means being selectively responsive to said ringing control switches to indicate which one of said 105 switches is operated, and means for bringing said indicating means into operative relation with any of said connecting circuits. 100

4. In a telephone system, the combination with telephone lines, of a connecting circuit 110 for establishing connection therewith, a switch closed while the connection is established, means for supplying ringing current of different characteristics, switching mechanism for selectively controlling the application of ringing current of said different characteristics to said connecting circuit, selecting keys for setting said switching mechanism to apply current of one sort or another, and holding means for maintaining 115 the setting of said switching mechanism, said holding means being under the alternative control of said first mentioned switch and said selecting keys. 120

5. In a telephone system, the combination 125 with a connecting circuit, means for supplying ringing current of different characteristics, switching mechanism for applying ringing current of said different characteristics to said connecting circuit, a plurality 130

- of electromagnetic switches for selectively controlling said switching mechanism, a selecting key associated with each of said electromagnetic switches, an energizing circuit for each electromagnetic switch adapted to be completed by the associated key, and locking circuits for said electromagnetic switches having a common branch controlled in contacts of each of said keys.
6. In a telephone system, the combination with a connecting circuit, of a ringing circuit having a plurality of branches, a controlling circuit having a corresponding number of branches, a locking relay for each of said controlling circuit branches adapted when operated to close the associated branch, a selecting key for controlling the operation of each locking relay, and an automatic switch adapted in its movement successively to establish the branches of said ringing circuit and come under the control of the corresponding branch of said controlling circuit.
7. In a telephone system, the combination with a connecting circuit, of a ringing circuit having a plurality of branches, a controlling circuit having corresponding branches, a selecting key for each branch of said controlling circuit adapted when operated to change the electrical condition of the associated branch, an automatic switch adapted in its movement successively to establish the branches of said ringing circuit and come under the control of the corresponding branch of said controlling circuit, and means responsive to the changed electrical condition of any one of said controlling branches for stopping said automatic switch.
8. In a telephone system, the combination with a connecting circuit, of a ringing circuit, having a plurality of branches, a controlling circuit having corresponding branches, means for changing the electrical condition of any of said controlling circuit branches, an automatic switch adapted in its movement successively to establish the branches of said ringing circuit, an electromagnetic stopping device for said switch responsive to the changed electrical condition of any of said controlling circuit branches, and means for bringing said stopping device into connection with said controlling circuit branches simultaneously with the establishing of the corresponding ringing circuit branches.
9. In a telephone system, the combination with a connecting circuit, of a normally open ringing circuit having a plurality of normally open branches, a controlling circuit having a corresponding number of branches, means for altering the electrical condition of any one of said controlling circuit branches, an automatic switch adapted in its
- movement successively to close the branches of said ringing circuit and simultaneously bring itself under the control of the corresponding branches of said controlling circuit, and means responsive to the changed electrical condition of any one of said controlling circuit branches for stopping said switch and closing said ringing circuit.
10. In a telephone system, the combination with a connecting circuit, of a normally open ringing circuit having a plurality of normally open branches, an automatic switch adapted in its movement successively to close said branches, means for closing said ringing circuit and stopping said switch at a waiting point immediately preceding a branch-closing position of the switch, and means for moving said switch from said waiting point to said branch-closing point.
11. In a telephone system, the combination with a connecting circuit, of a normally open ringing circuit having a plurality of normally open branches, an automatic switch adapted in its movement to close said branches successively, switching mechanism for closing said ringing circuit and simultaneously stopping said switch at a waiting point immediately preceding a branch-closing position, a source of pick-up impulses, means responsive to a pick-up impulse for moving said automatic switch from a waiting point to the corresponding branch-closing point, and a switch closed by said switching mechanism for rendering said means operative.
12. In a telephone system, the combination with a party line, of a connecting circuit, a ringing circuit therefor having a plurality of branches, sources of different sorts of current in said branches adapted for distinctively signaling the stations of said party line, a controlling circuit having branches corresponding with said ringing circuit branches, means for changing the electrical conditions of any one of said controlling circuit branches, an automatic switch adapted in its movement to establish successively the branches of said ringing circuit and bring itself under the control of corresponding branches of the controlling circuit, means responsive to the changed electrical condition of any controlling branch for stopping said switch to apply a particular sort of ringing current to the line, and means operated by the response of the called subscriber for moving said automatic switch to disconnect the ringing current and establish the talking condition of said circuit.
13. A telephone ringing circuit having a plurality of branches, an automatic switch adapted in its movement to establish said branches in succession, means for stopping said switch when a particular branch has been established, and means controlled by

the flow of current in the ringing circuit for moving, said switch out of the position in which it has been stopped.

14. The combination with a telephone connecting circuit, of a ringing circuit therefor having a plurality of branches, an automatic switch adapted in its movement to establish said branches in succession, means for stopping said switch in position to establish a particular branch, means for causing ringing current to flow over the branch thus

established, means controlled by the flow of ringing current to move said automatic switch out of position in which it has been stopped, and means operated in the further 15 movement of said switch to establish the talking condition of said connecting circuit.

In witness whereof, I hereunto subscribe my name this 27th day of December, A. D., 1915.

SAMUEL B. WILLIAMS, JR.
